UNITED STATES PATENT OFFICE.

FREDERICK A. SLICHTER, OF KANSAS CITY, MISSOURI, ASSIGNOR OF ONE-HALF TO
WILLIAM H. HOAGLAND, OF EL PASO, ILLINOIS.

VENDING-MACHINE.

936,051.

Specification of Letters Patent.

Patented Oct. 5, 1909.

Application filed April 14, 1909. Serial No. 489,775.

To all whom it may concern:

Be it known that I, FREDERICK A. SLICHTER, a citizen of the United States, and a resident of Kansas City, in the county of Jackson and State of Missouri, have invented a new and Improved Vending-Machine, of which the following is a full, clear, and exact description.

The object of the invention is to provide a new and improved vending machine, more especially designed for use in stores and other places, and arranged to allow convenient delivery of the merchandise in predetermined quantities, without danger of packing and obstructing the rapid flow of the merchandise, such as seeds of various kinds.

For the purpose mentioned the receptacle for containing the merchandise is provided at its bottom with a delivery chute, and a manually-controlled slide is mounted on the said bottom and extends through opposite sides of the receptacle, the slide having spaced measuring compartments open at the top and bottom for filling with the seed or other merchandise contained in the receptacle, and for delivering the seed in measured quantities to the said delivery chute on shifting the slide in either direction, and a cut-off held in the receptacle on top of the slide, to cut off the surplus merchandise from the compartment shifted into delivery position at the time.

A practical embodiment of the invention is represented in the accompanying drawings forming a part of this specification, in which similar characters of reference indicate corresponding parts in all the views.

Figure 1 is a perspective view of the improvement; Fig. 2 is an enlarged transverse section of the same; Fig. 3 is an enlarged side elevation of the same on the line 3—3 of Fig. 2; and Fig. 4 is a transverse section of a modified form of the improvement.

The improved vending machine is in the form of a cabinet A, adapted to be set on a counter or other support, and the cabinet is provided at the top with a cover B for filling one, two or more receptacles C, formed within the cabinet A, with seed or other merchandise to be vended. Each of the receptacles C has its bottom D provided with an aperture D', opening into a downwardly-extending delivery chute E, adapted to deliver the seed or other merchandise in measured quantities into a paper bag or other vessel. On

the bottom D within the receptacle C is mounted to slide in a transverse direction a slide F, preferably formed of two side pieces F' fitting into guideways C' arranged in the sides of the receptacle C, and the side pieces F' are rigidly connected with each other at or near their middle by a cross bar F², and the side pieces are also connected with each other by the end pieces F³ spaced from the cross bar F², so as to form measuring compartments G and G', adapted to fill with the seed or other merchandise contained in the receptacles C. The end pieces F³ may be adjusted nearer to or farther from the cross bar F², so as to increase or decrease the sizes of the compartments G and G' according to the amount of seed or other merchandise to be sold in a desired measured quantity. For the purpose mentioned the end pieces F³ are fastened by screws F⁵ to the side pieces F', each of the screws F⁵ engaging one of a series of apertures F⁴ formed in the side pieces F' and screwing into the end pieces F³. Thus by removing the screws F⁵ and shifting the end pieces F³ nearer to or farther from the cross bar F² and then fastening the end pieces F³ and the side pieces F' together by the screws F⁵, the sizes of the compartments G and G' can be regulated at will.

Within each receptacle C, directly above the slide F and in vertical alinement with the chute E is arranged a cut-off H in the form of a plate, pivoted at H' so as to rock and to cut off the surplus merchandise on shifting the slide F into discharge position. Each side of the cut-off plate is provided with a cam arm H², adapted to engage the corresponding piece F² at the time the slide F is shifted so as to swing the opposite side of the plate H down in firm contact with the upper surface of the slide F. Now the several parts are arranged in such a manner that when the slide F is in the position shown in Fig. 2, the previously filled compartment G is in register with the aperture D' and the chute E, so that the seed or other merchandise drops out of the compartment G and through the aperture D' and the chute E into a paper bag or other vessel held below. At the same time the other compartment G' fills with seed or other merchandise contained in the receptacle C, and when the slide F is now shifted from the left to the right then the compartment G' 110

is moved into delivery position over the chute E while the compartment G is moved into filling position. As both ends of the slide F project to the outside of the receptacle C, it is evident that the slide can be manipulated from either the front or the rear, and at each shifting of the slide a measured quantity of the material contained in the receptacle C is delivered to the paper bag or other vessel. The sliding movement of the slide F is limited in either direction by stops I attached to the under side of the slide near the outer ends thereof, to abut against the front and rear ends of the bottom D.

For some merchandise it is desirable that it be agitated, to prevent packing within the receptacle C, and for this purpose an agitator is provided, moving with the slide F.

The agitator shown in the drawings, consists essentially of a transversely extending bar J, mounted to slide in the front and rear of the receptacle C, and on the bar J are secured depending agitating arms K by the use of set screws L. The outer ends of the bar J are attached to brackets N, secured to the outer ends of the slide F, so that when the latter is shifted, the rod J and the agitating arms K move with the slide, thus agitating the merchandise contained in the receptacle C.

As illustrated in the modified form shown in Fig. 4, the cut-off H³ is peak shaped, with the ends close to the top of the slide and turned up, as indicated at H⁴, thus preventing skimming the surplus seed from the top of the compartment G or G' in delivery position relative to the chute E.

Having thus described my invention, I claim as new and desire to secure by Letters Patent:

1. A vending machine, comprising a receptacle for containing the merchandise, and provided at its bottom with an outlet chute, a manually-controlled measuring and delivering slide mounted to slide over the bottom of the receptacle and provided with spaced measuring compartments open at top and bottom and adapted to register alternately with the said outlet chute on moving the slide forward and backward, and a rocking cut-off mounted in the said receptacle above the slide and above the said outlet chute.

2. A vending machine, comprising a receptacle for containing the merchandise and provided at its bottom with an outlet chute, a manually-controlled measuring and delivering slide mounted to slide over the bottom of the receptacle and provided with spaced measuring compartments open at top and bottom and adapted to register alternately with the said outlet chute on moving the slide forward and backward, a rocking cut-off mounted in the said receptacle above the slide and above the said outlet chute, and

means whereby the slide will alternately rock the cut-off in opposite directions on shifting the slide forward and backward.

3. A vending machine, comprising a receptacle for containing the merchandise and provided at its bottom with an outlet chute, a manually-controlled measuring and delivering slide mounted to slide over the bottom of the receptacle and provided with spaced measuring compartments open at top and bottom and adapted to register alternately with the said outlet chute on moving the slide forward and backward, a rocking cut-off mounted in the said receptacle above the slide and above the said outlet chute, and cam arms on the said cut-off for engagement with the said slide to rock the cut-off in opposite directions on shifting the slide forward and backward.

4. A vending machine, comprising a receptacle for containing the merchandise and provided at its bottom with an outlet chute, a manually-controlled measuring and delivering slide mounted to slide over the bottom of the receptacle and provided with spaced measuring compartments open at top and bottom and adapted to register alternately with the said outlet chute on moving the slide forward and backward, and an agitator comprising a bar transversely slidably of the said receptacle and connected with the said slide to move with the latter.

5. A vending machine, comprising a receptacle for containing the merchandise, and provided at its bottom with an outlet chute, a manually-controlled measuring and delivering slide mounted to slide over the bottom of the receptacle and provided with spaced measuring compartments open at top and bottom and adapted to register alternately with the said outlet chute on moving the slide forward and backward, a rod extending through the front and rear of the receptacle and provided with depending stirring arms reaching approximately to the top of the slide, and brackets on the outer ends of the slide for supporting the terminals of the rod.

6. A vending machine comprising a casing provided with a bottom outlet, a slide movable transversely of the casing and provided with a plurality of openings therethrough arranged in alignment longitudinally of the slide and adapted to register alternately with the outlet when the slide is shifted longitudinally, and a swinging scraper above the outlet and co-operating with the upper face of the slide.

In testimony whereof I have signed my name to this specification in the presence of two subscribing witnesses.

FREDERICK A. SLICHTER.
